UNITED STATES PATENT OFFICE

157,009

DISPLAY CARD OR THE LIKE

Jack Silson, New York, N. Y.

Application September 10, 1948, Serial No. 148,543

Term of patent 3½ years

(Cl. D80—5)

To all whom it may concern:

Be it known that I, Jack Silson, a citizen of the United States of America, residing in New York, county of New York, and State of New York, have invented a new, original, and ornamental Design for a Display Card or the Like, of which the following is a specification, reference being had to the accompanying drawing, forming part thereof.

Fig. 1 is a plan view of a display card or the like, showing my new design.

Fig. 2 is an edge view thereof.

Fig. 3 is a plan view of the display card shown in Fig. 1, with the removable portion shown in separated condition.

I claim:

The ornamental design for a display card or the like, substantially as shown.

JACK SILSON.
